UNITED STATES PATENT OFFICE.

EDWARD B. HESS, OF BROOKLYN, NEW YORK, ASSIGNOR TO ROYAL TYPEWRITER COMPANY, INC., OF NEW YORK, N. Y., A CORPORATION OF NEW YORK.

PAPER-FEED DEVICE.

1,213,193.

Specification of Letters Patent. Patented Jan. 23, 1917.

Application filed August 24, 1916. Serial No. 116,605.

To all whom it may concern:

Be it known that I, EDWARD B. HESS, a citizen of the United States, residing in Brooklyn, in the county of Kings and State 5 of New York, have invented certain new and useful Improvements in Paper-Feed Devices, of which the following is a specification.

This invention relates particularly to devices for feeding writing or carbon paper from a roll or other source of supply to the platen of a typewriting machine, and the primary object of my invention is to employ a stationary paper supply support, *i. e.*, 10 one not moving with the carriage, and to associate therewith a guide for the paper which is so constructed and operated as to prevent uneven feeding of the paper or undue strain thereon when the carriage is 15 moved sidewise and during the line spacing 20 operation with the carriage in different positions.

In carrying out my invention I provide a guide for the paper as it passes from the 25 source of supply to the platen which is so constructed as to provide a looped or slack portion in the web so that during printing the paper is supplied to the machine for a considerable time from this slack portion, 30 and as soon as it is exhausted the guide is automatically operated to pull another slack portion from the supply and thereafter the machine is fed from a slack portion as before. In this way the carriage may be 35 moved sidewise and the paper fed for line spacing in any position of the carriage without such strain on any part of the paper as to produce irregularities in the 40 alignment of the printing on the paper. The preferred mechanism for accomplishing these results is hereafter more fully described.

In the accompanying drawings:—Figure 1 shows a front elevation of a typewriting 45 machine with paper feeding and guiding devices embodying my improvements applied thereto. Fig. 2 shows a side elevation of the same. Fig. 3 is a detail view showing the relation of the paper cutter to the 50 paper. Fig. 4 is a perspective view of the paper guide.

The typewriting machine may be of any usual kind, a Royal Standard machine being shown.

55 A indicates the platen and B a cross piece

carried by links *b* pivoted to the machine frame at *b'* and connected to springs *b''* which normally hold the cross piece close to the platen and also serve to hold the bar in its upward position when it is thrown 60 upward and rearward.

The roll of paper *P* is carried by arms *c* projecting forwardly from standards *C*, rising from the base *D*. The paper passes from the roll through a guide *G* and then 65 to the platen *A*. The guide is carried by supports *g* preferably in the form of wires or rods attached to arms *e* projecting rearwardly from the machine frame. The rods *g* are connected at their upper ends by a 70 cross piece *g'* which constitutes a fixed guide for the paper web. A movable guide for the web consists of a bail *g''* pivotally connected with the upper ends of the rods *g* and having a horizontally disposed cross 75 piece across which the paper extends. Springs *h* connected to the bail near its inner end and to the supports *g* by clips *h'* tend to hold the bail in its lowermost position and to return it thereto. The drawings show the paper web in three positions. The full lines *x* indicate the position of the web when it is taut; the dotted lines *y* indicate the condition of the web when it is 80 slack and the dotted lines *z* show its condition when the slack portion of the web is almost exhausted.

When printing, paper is drawn by the rotation of the platen from the slack portion 85 of the web which gradually diminishes in size as the work progresses, but by reason of the slack web the carriage may be moved freely sidewise without undue strain on the paper and the paper may be moved for line 90 spacing without irregularities in the feed or in printing of the lines. When the paper assumes the condition shown at *z* the bail is raised from its lowered position to the position shown by full lines at *g''* in Fig. 2, and 95 as soon as it reaches this position, or substantially this position, the springs *h* react and pull the web downward with a quick jerk causing the paper to unroll and produce another slack portion of the web. This operation occurs from time to time and the 100 slack portion of the web, possessing the advantages before described is thus maintained.

The cross bar *B* is preferably formed with 110 a knife edge *k* by means of which the paper

web may be cut. Fig. 2 shows the end of the paper at *p*. By taking hold of this end of the paper and pulling it against the knife edge while also pulling it forward and sideways the paper can be readily severed. The cross bar *B* serves the double purpose of guiding and severing the paper and may be raised and held out of operative position whenever desired.

10 While I have described one specific way of carrying out my invention it will be understood that my claims are not limited to the specific devices illustrated.

I claim as my invention:

15 1. A paper feed device for the platen of a typewriting machine comprising a source of supply for the paper web, and a swinging spring-actuated guide for the paper interposed between the platen and the source of supply for automatically producing a slack portion of the web between the source of supply and the platen while the paper is being fed.

20 2. A paper feed device for the platen of a typewriting machine comprising a source of supply for the paper web, a guide over which the paper passes, and a spring-actuated guide beneath which the paper passes interposed between the platen and source of supply for automatically producing a slack portion in the web between the source of supply and the platen.

25 3. A paper feed device for the platen of a typewriting machine comprising a source of supply for the paper web, a fixed guide over which the web passes, and a swinging spring-actuated guide for the paper interposed between the platen and source of sup-

ply and located below the fixed guide for automatically producing a slack portion in the web between the source of supply and the platen.

4. A paper feed device for the platen of a typewriting machine comprising a stationary support for a roll of paper, a fixed guide, another guide interposed between the platen and the web support and adapted to swing in a vertical plane, and a spring for swinging said last-mentioned guide downward to produce a slack looped portion in the web between the roll and the platen when said guide is raised to a predetermined extent.

5. A paper feed device, comprising a support for the web, a fixed guide, another guide adapted to swing in a vertical plane, and a spring for swinging said guide downward to produce a looped portion in the web when said guide is raised to a predetermined extent.

6. A paper feed device, comprising a stationary support for a roll of paper and a guide for the paper web, comprising a fixed portion over which the paper passes, a bail engaging the web and pivoted to move in a vertical plane, and a spring tending to draw the bail downward and which pulls said bail away from the roll when the bail is raised to a predetermined extent and the tension of the spring is sufficiently increased.

In testimony whereof, I have hereunto subscribed my name:

EDWARD B. HESS.
